His ATTORNEY

UNITED STATES PATENT OFFICE

HARRY FRANKLIN ARMSTRONG, OF BRANDON, MANITOBA, CANADA

MAIL-BAG FASTENER AND LABEL HOLDER

Application filed September 16, 1929, Serial No. 392,984, and in Canada February 7, 1929.

This present invention relates to new and useful improvements in a mail bag fastener and label holder and has for its primary object the provision of a simple and efficient structure which will serve to remove or at least partially remove the label when opening the fastener.

Another object of the invention resides in the provision of a mail bag fastener and label holder of the character stated which may be readily adjusted on the mail bag closure cord and then closed to lock the same in adjusted position, after which the label is inserted in the fastener.

15 A further object of the invention resides in the provision of a mail bag fastener and label holder of the character stated which is constructed in such a manner that the rope clamping member also serves to raise and 20 remove a portion of the label when moved to its inoperative position in opening the fastener to permit the latter to slide on the rope and thus allow opening of the mail bag.

A still further object of the invention resides 25 in the provision of a mail bag fastener and label holder of the character stated which is formed in such a manner that the rope gripping member is pivoted in the body of the fastener in such a manner that when in 30 its operative position to grip the mail bag closure rope, it is also in position to permit insertion of the label in the body and when the rope gripping member is swung to its inoperative position, it raises and partially 35 removes the label.

A still further object of the invention resides 40 in the provision of a mail bag fastener and label holder of the character stated which includes an elongated body in one open side of which the label is removably held with a portion thereof extending over the rope gripping member so that when the latter is swung from its operative position to its inoperative position to release the rope and thus permit 45 movement of the fastener on the rope, the label is raised and forced out at one end to partially remove the label.

A still further object of the invention resides 50 in the provision of a mail bag fastener and label holder of the character stated in

which the rope is firmly gripped within the body and the fastener thus retained in adjusted position on the rope as long as the rope gripping member is left in its operative position.

55 A still further object of the invention resides in the provision of a mail bag fastener and label holder of the character stated which is of simple and inexpensive construction, composed of the minimum number of parts 60 and highly efficient in operation.

To the accomplishment of these and related objects as shall become apparent as the description proceeds my invention resides 65 in the construction, combination and arrangement of parts as shall be hereinafter more fully described, illustrated in the accompanying drawings and pointed out in the claims hereunto appended.

The invention will be best understood and 70 can be more clearly described, when reference is had to the drawings forming a part of this disclosure wherein like characters indicate like parts throughout the several views.

In the drawings:—

75 Figure 1 is a perspective view of the mail bag fastener and label holder, in use with the same locked in adjusted position on the rope;

Figure 2 is a plan view of the device as disclosed in Figure 1, but showing the device 80 with the label removed;

Figure 3 is a longitudinal section through the device, taken substantially on the plane of line 3—3 of Figure 2, looking in the direction indicated by the arrows and showing 85 the label in position; and

Figure 4 is a view similar to Figure 3, showing the rope gripping member raised to its inoperative position and forcing outwardly the end of the label to partially remove 90 the same.

Referring more in detail to the drawings, it will be noted that the body 6 of the device is of elongated form and hollow. The upper and lower walls 7 and 8 of the body 6 are provided respectively with openings 9 and 10 near their rear ends by cutting away portions thereof. It is also to be noted that the upper wall 7 is positioned inwardly of the upper edge of the body 6 and the latter 95

100

is turned inwardly to provide inturned flanges 11 for holding in position the label 12 placed in the upper side of the body 6, owing to the flanges 11 extending over the edges 5 of the label 12. The body 6 is provided at its forward end with a pair of spaced openings 13 through which the rope 14 extends as well as through the registering openings 15 provided at the rear end of the body 6, the looped portion 16 of the rope 14, outwardly of the rear end of the body 6 serving to limit outward or rearward movement of the device on the rope 14 and thus prevent the device from being withdrawn from the rope 14. 10 The rope 14 also has one portion extending through the upturned portion 17 of the rope gripping member 18, within the body 6 and near the rear end thereof. Thus, this section or portion of the rope 14 is raised and 15 extended over the rope gripping member throughout substantially the entire length of the latter and over the corrugated gripping end 19 thereof, while the other portion or section of the rope 14 extends loosely through 20 the body 6 and is engaged only by the transversely corrugated gripping end 19 of the member 18 and thus pressed together with the first mentioned portion or section of the rope 14, between the gripping end 19 of the 25 member 18 and the inner face of the body upper wall 7, when the member 18 is in operative position to lock the device against movement on the rope 14. The member 18 is fulcrumed on the fulcrum pin 20 which extends 30 transversely through the forward portion of the member 18 and through the lower part of the body 6, intermediate the ends thereof. The fulcrum pin 20 is thus located just rearwardly of the main portion of the upper wall 35 7 and just forwardly of the rear end of the main portion of the bottom wall 18 of the body 6. The rear upper end of the member 18 is enlarged and flattened to provide a wide flat handle 21 extending across the rear end of the body 6 with its side portions 22 turned 40 down for engagement over the sides of the body 6 when the member 18 is in its normal or operative position. The label 12 will lie flat in the upper side of the body 6 with its 45 rear end extending substantially to the outwardly curved portion of the member 18 and over the main portion of the latter and the rope section resting thereon. Thus, when the member is swung on its fulcrum pin 20 to 50 inoperative position, the main portion of the member 18 and the rope portion resting thereon work outwardly through the opening 9 in the upper wall 7 of the body 6 and raise the rear end of the label 12 out of the body 55 6 to partially remove the label 12 while at the same time releasing the rope 14 to permit movement of the device longitudinally of the rope 14 for opening of the mail bag.

As the construction of the device has thus been described in detail, brief reference is

now had to its use and modus operandi: After the rope 14 has been properly threaded through the body 6 and one portion or section of the rope extended through the curved or turned portion of the rope gripping member 18, the device may be freely adjusted longitudinally of the rope 14 as long as the member 18 is in its raised or inoperative position. As soon as the member 18 is swung on its fulcrum pin 20 to operative position, however, the forward gripping end 19 thereof 70 serves to firmly grip both rope portions or sections and press them against the underface of the upper wall 7 of the body 6, thus firmly locking the device against movement on the rope 14. When in this condition the device will also firmly hold the label 12 placed in the upper side of the body 6. When it is desired to open the mail bag, the body 6 is held and the member 18 is swung outwardly on its 75 fulcrum pin 20 to inoperative position by means of the flat handle end 21. This movement of the member 18 serves to release the rope portions or sections to permit movement of the device longitudinally of the rope 14 and at the same time raises and forces outwardly the rear end of the label 12 to partially remove the latter. 80

From the foregoing description, taken in connection with the accompanying drawings, 85 it will be manifest that a mail bag fastener and label holder is provided that will fulfill all the necessary requirements of such a device, but as many changes could be made in the above description and many apparently 90 widely different embodiments of my invention may be constructed within the scope of the appended claims without departing from the spirit or scope thereof, it is intended that all matters contained in the said accompanying 95 specification and drawings, shall be interpreted as illustrative and not in a limited sense. 100

Having thus described my invention, what I claim as new and desire to secure by Letters Patent is:— 110

1. A mail bag fastener and label holder including a body slidable on rope sections and provided with a label accommodating pocket in one face; and a rope gripping member fulcrumed in said body and operating through said label accommodating pocket to raise and partially remove the label when said rope gripping member is moved to its inoperative position. 115

2. A mail bag fastener and label holder including a body having a label accommodating pocket therein; said body being constructed for longitudinal adjustment on rope sections; and a member fulcrumed within said body and extending through said label accommodating pocket; said member gripping the rope sections and holding the body in adjusted position on said rope sections when said member is in its operative position. 120

tion; said member operating through said label accommodating pocket to partially remove the label when said member is moved to its inoperative position.

5 3. A mail bag fastener and label holder including a body adjustable longitudinally on parallel rope sections; and a rope gripping member fulcrumed within said body and operating through one wall thereof when being moved to its operative and inoperative positions; said body holding a label with a portion of the latter extending over said member and in the path of movement thereof so that the label is partially removed by said 10 member during movement of the latter from its operative position to its inoperative position.

4. A mail bag fastener and label holder including a hollow rectangular body slidable on rope sections and provided in its upper side with a label accommodating pocket; said body having openings in the upper and lower walls thereof adjacent one end of the body; and a rope gripping member fulcrumed 20 in said body and having an angularly extended intermediate portion with an opening therethrough for one of the rope sections; said member having a rope section gripping end for co-operation with the inner face of 25 the upper wall of said body to grip said rope section when the said rope gripping member is in its operative position; said intermediate portion of the rope gripping member operating through the label accommodating 30 pocket to raise and partly remove the label from said pocket when said rope gripping member is operated through said label accommodating pocket when said rope gripping member is moved to its inoperative 35 position.

5. A mail bag fastener and label holder including a hollow body of rectangular form adjustable longitudinally on parallel rope sections; said body having a label accommodating opening in one face; and a rope gripping member fulcrumed in the centre of said body and having a short arm for pressing the rope sections against the inner face of one wall of said body to grip said rope sections 40 when the said rope gripping member is in its operative position within said body; said rope gripping member having an angular intermediate portion with a rope section passing therethrough and an outer end with downturned flanges engaged over the end of said body when said rope gripping member is in its operative position; said intermediate portion of said rope gripping member extending through and operating in said label 45 accommodating pocket of the body together with part of the main portion of said rope gripping member to raise an end of the label from within said label accommodating pocket 50 and partially remove the label as the said 55

rope gripping member is moved from its operative position to its inoperative position.

In testimony whereof I hereunto affix my signature.
